UNITED STATES PATENT OFFICE.

WILLIAM DANIEL HUFF, OF LA FAYETTE, LOUISIANA, ASSIGNOR OF THREE-FOURTHS
TO LOUISE GUIDRY MOSS, OF NEW IBERIA, LOUISIANA.

APPARATUS FOR OPERATING SULFUR-WELLS.

1,170,266.

Specification of Letters Patent.

Patented Feb. 1, 1916.

Application filed April 21, 1915, Serial No. 22,874. Renewed December 27, 1915. Serial No. 68,922.

To all whom it may concern:

Be it known that I, WILLIAM DANIEL HUFF, a citizen of the United States, residing at La Fayette, in the parish of La Fayette and State of Louisiana, have invented certain new and useful Improvements in Apparatus for Operating Sulfur-Wells; and I do hereby declare the following to be a full, clear, and exact description 10 of the invention, such as will enable others skilled in the art to which it appertains to make and use the same.

My present invention relates to the operation of sulfur wells, especially to those wells 15 in which the sulfur is caused to flow by fusion into the bottom of a casing, and is lifted therefrom by an air jet acting after the manner of the well known aerial column.

According to the present method of operation of sulfur wells, it is customary to inject hot water from the surface down into the sulfur-bearing strata, which hot water, percolating through these strata, melts the sulfur and the sulfur flows down 25 into the bottom of the cavity which has been previously excavated in drilling the well. The sulfur will form a layer beneath the water in this cavity because of its greater specific gravity. The temperature 30 of the water should be high enough to melt the sulfur, but not so high as to cause it to assume the viscous or allotropic condition, which condition is generally reached at a temperature of about 380° F.

In all of the sulfur mines with which I am familiar, there is more or less water already contained in or above the sulfur-bearing strata, and it is the purpose of my invention to heat this water already naturally occurring to the proper temperature to melt the sulfur, and then to lift the sulfur up from the mine without the necessity for using any heating apparatus whatsoever on the surface of the ground. If, however, there should not be sufficient water *in situ* to accomplish the desired result, an additional supply of water can be pumped down into the casing from the surface and allowed to flow out of the bottom thereof into 50 the sulfur-bearing strata at the bottom of the well. In other words, the purpose of my present invention is to apply the heat locally at the bottom of the well and heat the water already found there, to cause the 55 convection currents of this water so heated

to percolate through the sulfur-bearing strata and to melt the sulfur, and finally, by means of an air jet, to lift the sulfur so melted up from the mine to the surface of the ground. In order to accomplish 60 these results, I provide an improved form of burner adapted to be located within the well casing, and adapted to supply the necessary amount of heat. For this purpose, I use a hydrocarbon burner, or a series of 65 burners, which may be adapted to be used with any suitable hydrocarbon liquid, such as crude oil, and which may be primed with a lighter or more volatile oil, the supply of which latter oil is cut off when the 70 temperature is sufficient to use the heavier oil, as will be hereinafter more fully described. The burner is provided with electrical means for initially warming the same, and also with an electric igniter for starting 75 the ignition. The electric current is cut off after the burner is in operation; the electric current being used only for a brief interval at the time of starting, for heating the burner and igniting the mixture of 80 hydrocarbon oil and air.

My invention will be understood by reference to the accompanying drawings, in which similar parts are indicated by similar reference symbols throughout the several 85 views.

Figure 1 shows a central vertical section through the well casing, with the parts enclosed therein shown partly broken away and partly in elevation, and it also shows 90 in diagrammatic form the apparatus used above the surface of the ground; Fig. 2 shows a section through the group of burners along the line 2—2 of Figs. 1 and 3, and looking down; Fig. 3 shows a vertical 95 section through the group of burners along the line 3—3 of Fig. 2, and looking in the direction of the arrows; Fig. 4 is a detail showing a suitable form of electric heater for warming up one of the group of burners; Fig. 5 is a diagram showing the group of electric heaters and igniters with their connections; and Fig. 6 is a detail showing one form of air jet used for lifting the melted sulfur.

Referring first to Fig. 1, 1 represents the well casing constructed in the usual way, but provided with perforations near its bottom, as at 2; instead of these perforations the ordinary well screen may be used if de- 110

sired. The bottom of the well casing is preferably closed with a cap 3. The top of the well casing is provided with a perforated cap 4, into which the upper ends of the 5 group of pipes or flues 5, for carrying off the products of combustion from the individual burners, are secured. Above this perforated cap 4 is a closed perforated chamber 6, into which the products of combustion 10 from the several burners enter, and from which they are carried off by the delivery pipe 7. Projecting through the upper end of the casing is the delivery pipe 8 for delivering the melted sulfur to the top of the 15 mine, which is carried off by a pipe 9 into any suitable receptacle, not shown. To the upper end of this pipe 8 any suitable hoisting arrangement may be attached, such as the bail 10 and the hook 11, the latter being 20 attached to any suitable tackle, not shown, which is suspended from the derrick, not shown, which is ordinarily used in installing and maintaining the well. Surrounding this inner pipe 8, near its bottom, is a hollow annular member, preferably a casting, 20, provided with a closed annular air chamber 21. This member 20 is provided with a series of cylindrical flanges 22, threaded exteriorly to engage the flues 5, and internally to engage 25 the bases 23 of the air jets 24 of the burners, which air jets are surrounded with a tapered casing 25, in which are contained hollow conical electric heaters 26. Mounted inside the air jets 24, and concentric therewith, 30 are the oil jets 27 connected to the annular oil chamber 28 mounted in the air chamber 21. This annular oil chamber is adjustably supported from the bottom of the casting 20 by means of the milled-headed screws 29. 35 For convenience of assembly, I provide circular screw caps 20^a and 28^a in the bottom of the air and oil chambers, respectively. A perforated shell 30 is mounted above, and surrounds, the air and oil jets of each burner, 40 and an electric igniter 31 is provided for each burner, whose connections will be hereinafter described. In the inner pipe 8 an air pipe 33 projects downward and terminates in a suitable head 34, provided with 45 a plurality of orifices 35 adapted to blow the air upward and to cause it to lift the melted sulfur.

Instead of the form of air jet shown, any suitable form may be adopted if desired.

50 Compressed air is supplied to the air chamber 21 and the pipe 33 from any suitable source of compressed air, such as the air compressor 36, through the pipes 37 and 38, respectively, which pipes are controlled 55 by the valves 37^a and 38^a.

Oil is supplied to the apparatus from any suitable source, such as the tank 40 and the pipe 41, the supply being controlled by the valve 41^a, and this pipe 41 leads down to 60 the oil chamber 28 and supplies oil to the

burners. If it is desired to accelerate the draft in the flues 5, the delivery pipe 7 for the products of combustion may be connected to a suction fan 50, discharging through the pipe 51, or it may be provided 70 with a delivery branch 52 in which an air jet 53 is mounted, as shown in Fig. 1, which air jet may be supplied with compressed air by the pipe 54 connected to the pipe 38 and controlled by the valve 55^a.

75 Electricity is furnished from any suitable source of power, indicated by the dynamo 60 in Fig. 1, and it is supplied to the heater and to the igniter from a suitable switch-board, such as 61; but these do not constitute a part of my present invention and are shown diagrammatically in Fig. 1.

80 The electric heaters 26 are preferably formed of hollow cones 66, as shown in Fig. 4, made of mica, or other suitable material, on which the heating wires 62 are stretched, as shown in Fig. 4, and these wires are connected to a suitable insulated cable 63, as shown in Fig. 5, the end of which is made long enough to be properly connected up in 85 the air chamber 21 to the main cable 64 leading to the source of electricity. I prefer to have an all metallic circuit, comprising two wires bound in each cable so as to avoid the corrosion, or other injuries to the conductors, or to their insulation, incident to mining operations of this character; but if desired one of the terminals may be grounded to any 90 part of the well casing and the other terminal connected to the heater.

95 The electric igniters 31 are preferably in shunt circuit with the heaters, and the fine wire 65, which is heated by the current, is preferably located at one side of the burner jet, so as to be clear of the path of the 100 mingled air and oil gases in the burner during the operation of the same.

Additional water may be admitted to the interior of the well, if desired, through the pipe 70, leading from any suitable source, 110 not shown, such as a pump, water main, overhead tank, or the like.

115 The operation of the apparatus is as follows: To start the device, turn on the electric current at the switch-board 61 and warm up the burners, then turn on the air to the air chamber 21 through the pipe 37, and then turn on the gasoline through the pipe 41 to the gasoline chamber 28. The gasoline will flow up through the oil jets 27 and will be mixed with the air rushing through the air jets 24 and, being sufficiently warmed by the electric heater, will be ignited by the igniter 31, and the oil burners will begin to operate. In a short while the heat of the oil 120 burners will heat up all the contiguous parts sufficiently to enable the apparatus to continue in operation after the electric current is cut off, and the electric current is then 125 shut off and combustion continues. The prod- 130

ucts of combustion are carried up through the flues 5 and out through the pipe 7, with or without the assistance of the fan 50 and the jet 53. If it is desired to facilitate the 5 draft through the flues, the fan 50, driven by any suitable source of power, may be employed, or the compressed air may be turned on through the pipe 54 to the jet 53, or both fan and jet may be used, if desired. As soon 10 as the melted sulfur has accumulated to a sufficient height in the bottom of the casing, air is turned on through the pipe 33, causing the air to flow upward through the apertures 35 in the air jet 34, lifting the column 15 of melted sulfur upward in the inner pipe 8 and delivering it through the pipe 9. It will be seen that the supply of air used in the air lift will be heated, before entering the sulfur, by the burners and that the burners 20 will heat the water in the bottom of the well, causing convection currents to flow around the casing and into the sulfur-bearing strata, melting the sulfur and causing the same to flow through the screen or perforations provided near the bottom of the 25 well casing. Thus it will be seen that the water found at the bottom of the well will serve as a medium to convey the heat to the sulfur to melt the same, and that the sulfur, owing to its greater specific gravity, will 30 flow down, forming a layer beneath the hot water, and will ultimately rise in the inner pipe 8 to a sufficient height to be lifted by the air lift just described. It will generally be 35 found that there is an ample sufficiency of water in such wells to permit a natural supply for the transference of the heat from the burners to the sulfur as just described; but in case there should not be sufficient water 40 for this purpose, additional water may be supplied through the pipe 70, and in case the sulfur-bearing strata should be dry or approximately dry of water, the total quantity of water required may be supplied 45 through the pipe 70. The natural conditions found at the bottom of the well will generally prevent the water from becoming heated to such a high temperature as would cause the sulfur to assume the viscous or 50 allotropic form, and this temperature may be controlled by regulating the supply of oil and water to the burners. If, however, it is desired to note the temperature at the bottom of the well, one or more suitable thermometers, well known in the arts, may be 55 located in the bottom of the well, with means for reading same at the surface thereof. Such thermometers are well known in the arts, and not being a part of my invention 60 are not shown herein.

It will be noted that the inner pipe 8 may be raised or lowered, if desired, so that it may be adapted to the height of the sulfur flowing into the lower part of the well casing 65. The water flowing into the well casing

around the burners will prevent the temperature from becoming excessively high, or high enough to affect the flow of the sulfur in the inner pipe.

It will be noted that the electric heater is 70 contained in a water-tight casing, and thus is protected from the effects of either water or even moisture.

While I have shown the apparatus in its preferred form it will be obvious that various modifications might be made in the same, and various changes in the construction, combination and arrangement of parts which could be used without departing from the spirit of my invention. 75

Having thus described my invention what I claim and desire to secure by Letters Patent of the United States is:—

1. An apparatus for operating sulfur mines, comprising a well casing provided 85 with perforations near its bottom, hydrocarbon burners contained in said casing near the bottom thereof for heating the water in the well, and causing the same to melt the sulfur, a central pipe to carry off the fused 90 products projecting down in said casing between the burners, an air tube mounted in said pipe and provided with an air jet at its lower end, and means for supplying air under pressure to said tube, substantially as 95 described.

2. An apparatus for operating sulfur mines, comprising a well casing provided with perforations near its bottom, hydrocarbon burners mounted in said casing near 100 the bottom thereof for heating the water in the well, and causing the same to melt the sulfur, a central pipe and means for elevating the fused material from the well, substantially as described. 105

3. An apparatus for operating sulfur mines, comprising a well casing provided with perforations near its bottom, hydrocarbon burners mounted in said casing near the bottom thereof for heating the water in the 110 well, and causing the same to melt the sulfur, with means for supplying oil and air to the base of said burners and for carrying off the products of combustion therefrom, a central pipe and means for elevating the fused 115 material from the well, substantially as described.

4. An apparatus for operating sulfur mines, comprising a well casing provided with perforations near its bottom, hydrocarbon burners mounted in said casing near the bottom thereof for heating the water in the well, and causing the same to melt the sulfur, electric heaters and igniters for warming up said burners and for igniting same, 120 a central pipe and means for elevating the fused material from the well, substantially as described.

5. An apparatus for operating sulfur mines, comprising a well casing provided 130

with perforations near its bottom, hydrocarbon burners mounted in said casing near the bottom thereof for heating the water in the wells, and causing the same to melt the sulfur, with means for supplying oil and air to the base of said burners and for carrying off the products of combustion therefrom, electric heaters and igniters for warming up said burners and for igniting same, a central pipe and means for elevating the fused material from the well, substantially as described.

6. An apparatus for operating sulfur mines, comprising a well casing provided with perforations near its bottom, means contained in said casing near the bottom thereof for heating the water in the well, and causing the same to melt the sulfur, said means comprising an annular air chamber mounted in said casing, an annular oil chamber mounted in said air chamber, hydrocarbon burners mounted above said annular air chamber, and connected to said air and oil chambers, flues for carrying off the products of combustion from said burners, means for supplying air and oil, respectively, to said air and oil chambers, a central pipe and means for elevating the fused material from the well, substantially as described.

7. An apparatus for operating sulfur mines, comprising a well casing provided with perforations near its bottom, means contained in said casing near the bottom thereof for heating the water in the well, and causing the same to melt the sulfur, said means comprising an annular air chamber mounted in said casing, an annular oil chamber mounted in said air chamber, hydrocarbon burners mounted above said annular air chamber, and connected to said air and oil chambers, flues for carrying off the products of combustion from said burners, means for supplying air and oil, respectively, to said air and oil chambers, electric heaters surrounding said burners for initially warming same, and electric igniters at said burners for starting combustion, a central pipe and means for elevating the fused material from the well, substantially as described.

8. An apparatus for operating sulfur mines, comprising a well casing provided with perforations near its bottom, means contained in said casing near the bottom thereof for heating the water in the well, and causing the same to melt the sulfur, said means comprising an annular air chamber mounted in said casing, an annular oil chamber mounted in said air chamber, hydrocarbon burners mounted above said annular chamber, and connected to said air and oil chambers, flues for carrying off the products of combustion from said burners, means located exterior to said casing for accelerating the draft in said flues, means for supplying air and oil, respectively, to said air and oil chambers, a central pipe and

means for elevating the fused material from the well, substantially as described.

9. An apparatus for operating sulfur mines, comprising a well casing provided with perforations near its bottom, means contained in said casing near the bottom thereof for heating the water in the well, and causing the same to melt the sulfur, said means comprising an annular air chamber mounted in said casing, an annular oil chamber mounted in said air chamber, hydrocarbon burners mounted above said annular air chamber, and connected to said air and oil chambers, flues for carrying off the products of combustion from said burners, means located exterior to said casing for accelerating the draft in said flues, means for supplying air and oil, respectively, to said air and oil chambers, electric heaters surrounding said burners for initially warming same, and electric igniters at said burners for starting combustion, a central pipe and means for elevating the fused material from the well, substantially as described.

10. An apparatus for operating sulfur mines, comprising a well casing provided with perforations near its bottom, hydrocarbon burners mounted in said casing near the bottom thereof for heating the water in the well, and causing the same to melt the sulfur, a central pipe to carry off the fused products, projecting down in said casing between said burners, an air tube mounted in said pipe, and provided with an air jet at its lower end, and means for supplying air under pressure to said tube, substantially as described.

11. An apparatus for operating sulfur mines, comprising a well casing provided with perforations near its bottom, hydrocarbon burners mounted in said casing near the bottom thereof for heating the water in the well, and causing the same to melt the sulfur, with means for supplying oil and air to the base of said burners and for carrying off the products of combustion therefrom, a central pipe projecting down in said casing between said burners for carrying off the fused products, an air tube mounted in said pipe and provided with an air jet at its lower end, and means for supplying air under pressure to said tube, substantially as described.

12. An apparatus for operating sulfur mines, comprising a well casing provided with perforations near its bottom, means contained in said casing near the bottom thereof for heating the water in the well, and causing the same to melt the sulfur, said means comprising an annular air chamber mounted in said casing, an annular oil chamber mounted in said air chamber, hydrocarbon burners mounted above said annular air chamber, and connected to said air and oil chambers, a central pipe and

oil chambers, flues for carrying off the products of combustion from said burners, means for supplying air and oil, respectively, to said air and oil chambers, a casing surrounding each burner, an electric heater mounted in each casing, a central pipe and means for elevating the fused material from the well, substantially as described.

13. An apparatus for operating sulfur mines, comprising a well casing provided with perforations near its bottom, means contained in said casing near the bottom thereof for heating the water in the well, and causing the same to melt the sulfur, said means comprising an annular air chamber mounted in said casing, an annular oil chamber mounted in said air chamber, hydrocarbon burners mounted above said annular air chamber, and connected to said air and oil chambers, flues for carrying off the products of combustion from said burners, means for supplying air and oil, respectively, to said air and oil chambers, a casing surrounding said burner, an electric heater mounted in each casing, an electric igniter for each burner, located at one side of the direct path of the flame, a central pipe and means for elevating the fused material from the well, substantially as described.

30 14. An apparatus for operating sulfur mines, comprising a well casing provided with perforations near its bottom, hydrocarbon burners mounted in said casing near the bottom thereof for heating the water in the well, and causing the same to melt the sulfur, a casing surrounding each burner, an electric heater mounted in each casing, and an electric igniter for igniting said burner, a central pipe and means for elevating the fused material from the well, substantially as described.

15. An apparatus for operating sulfur mines, comprising a well casing provided with perforations near its bottom, hydrocarbon burners mounted in said casing near the bottom thereof for heating the water in the well, and causing the same to melt the sulfur, a casing surrounding each burner, an electric heater mounted in each casing, and an electric igniter for igniting said burner, an electric igniter for each burner, located at one side of the direct path of the flame, a central pipe and means for elevating the fused material from the well, substantially as described.

16. An apparatus for operating sulfur mines, comprising a well casing provided with perforations near its bottom, means for supplying water to the interior of said casing, hydrocarbon burners mounted in said casing near the bottom thereof for heating the water in the well, and causing the same to melt the sulfur, with means for supplying oil and air to the base of said burners and for carrying off the products of com-

bustion therefrom, electric heaters and igniters for warming up said burners and for igniting same, a central pipe and means for elevating the fused material from the well, substantially as described.

17. An apparatus for operating sulfur mines, comprising a well casing provided with perforations near its bottom, means for supplying water to the interior of said casing, hydrocarbon burners mounted in said casing near the bottom thereof for heating the water in the well, and causing the same to melt the sulfur, a central pipe for carrying off the fused products, projecting down in said casing between said burners, an air tube mounted in said pipe and provided with an air jet at its lower end, and means for supplying air under pressure to said tube, substantially as described.

18. An apparatus for operating sulfur mines, comprising a well casing provided with perforations near its bottom, means for supplying water to the interior of said casing, hydrocarbon burners mounted in said casing near the bottom thereof for heating the water in the well, and causing the same to melt the sulfur, with means for supplying oil and air to the base of said burners and for carrying off the products of combustion therefrom, a central pipe for carrying off the fused products, projecting down in said casing between said burners, an air tube mounted in said pipe and provided with an air jet at its lower end, and means for supplying air under pressure to said tube, substantially as described.

19. An apparatus for operating sulfur mines, comprising a well casing provided with perforations near its bottom, means for supplying water to the interior of said casing, means contained in said casing near the bottom thereof for heating the water in the well, and causing the same to melt the sulfur, said means comprising an annular air chamber mounted in said casing, an annular oil chamber mounted in said air chamber, hydrocarbon burners mounted above said annular air chamber, and connected to said air and oil chambers, flues for carrying off the products of combustion from said burners, means located exterior to said casing for accelerating the draft in said flues, means for supplying air and oil, respectively, to said air and oil chambers, a central pipe and means for elevating the fused material from the well, substantially as described.

20. An apparatus for operating sulfur mines, comprising a well casing provided with perforations near its bottom, means for supplying water to the interior of said casing, means contained in said casing near the bottom thereof for heating the water in the well, and causing the same to melt the sulfur, said means comprising an annular air

chamber mounted in said casing, an annular oil chamber mounted in said air chamber, hydrocarbon burners mounted above said annular air chamber, and connected to said air and oil chambers, flues for carrying off the products of combustion from said burners, means located exterior to said casing for accelerating the draft in said flues, means for supplying air and oil, respectively, to said air and oil chambers, electric heaters surrounding said burners for initially warming same, and electric igniters at said burners for starting combustion, a central pipe and means for elevating the fused material from the well, substantially as described.

21. An apparatus for operating sulfur mines, comprising a well casing provided with perforations near its bottom, means for supplying water to the interior of said casing, means contained in said casing near

the bottom thereof for heating the water in the well, and causing the same to melt the sulfur, said means comprising an annular air chamber mounted in said casing, an annular oil chamber mounted in said air chamber, hydrocarbon burners mounted above said annular air chamber, and connected to said air and oil chambers, flues for carrying off the products of combustion from said burners, means for supplying air and oil, respectively, to said air and oil chambers, electric heaters surrounding said burners for initially warming same, and electric igniters at said burners for starting combustion, a central pipe and means for elevating the fused material from the well, substantially as described.

In testimony whereof, I affix my signature.

WILLIAM DANIEL HUFF.
